(57) **CLAIM**

The ornamental design for a medical article retainer, as shown
and described.

DESCRIPTION

FIG. 1 is a perspective view of a medical article retainer
configured in accordance with the present invention;

FIG. 2 is a top view thereof;

FIG. 3 is a cross-sectional view thereof taken along line 3—3
shown in FIG. 2;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken line showing is included for the purpose of illustrating
portions of the catheter retainer and forms no part of
the claimed design.
